UNITED STATES PATENT OFFICE.

ERNST R. SCHROEDER AND CHARLES M. MILLER, OF ALAMEDA, CALIFORNIA.

PROCESS AND APPARATUS FOR MAKING PORCELAIN INLAYS.

1,211,244.

Specification of Letters Patent.

Patented Jan. 2, 1917.

Application filed January 25, 1916. Serial No. 74,127.

To all whom it may concern:

Be it known that we, ERNST R. SCHROEDER and CHARLES M. MILLER, citizens of the United States of America, and residents of 5 Alameda, county of Alameda, State of California, have invented a new and useful Process and Apparatus for Making Porcelain Inlays, of which the following is a specification.

10 Our invention relates to a new method of producing porcelain inlays in the practice of dental surgery.

An object of our invention is to provide improved means with which accurate inlays 15 may be more easily obtained.

Another object of our invention is to provide an improved process for making inlays.

20 A further object of our invention is to provide a process for making porcelain inlays, by the practice of which the cavity in the tooth structure is accurately fitted by the inlay and perfect marginal contact between tooth and inlay is secured.

25 The invention possesses other features of advantage which, with the foregoing, will be set forth in the following description of the preferred form of our invention which is illustrated in the drawings accompanying and forming part of the specification. It 30 is to be understood that we do not limit ourselves to the showing made by the said drawings and description, as we may adopt variations of the preferred form within the scope of our invention as set forth in the claims.

35 Referring to the drawings: Figure 1 is a view of a tooth showing a wax impression in the cavity which is to receive the inlay. Fig. 2 is a sectional view of the metal positive of the cavity cast from the wax pattern. Fig. 3 is a sectional view of the positive coated on the rear surface with wax. Fig. 4 is a sectional view through the mold, showing the wax coated positive invested therein. Fig. 5 is a similar view after the 45 wax has been eliminated, showing the mold ready to pour to form the negative of the tooth cavity. Fig. 6 is a sectional view of the negative or matrix casting. Fig. 7 is a sectional view of the negative filled with 50 porcelain mixture. Fig. 8 is a sectional view through the porcelain inlay.

In broad outline our invention consists in providing a relatively heavy and rigid cast body or block having a cavity which is an

exact duplicate of the cavity in the tooth so 55 that the inlay which is prepared in this matrix block or negative, may be transposed to the tooth cavity and will accurately fit therein and make perfect marginal contact therewith; and our invention further 60 consists in the process by which said negative is formed and the process by which the inlay is prepared therein.

In practising our process, the cavity in the tooth is first properly excavated and prepared to the precise form into which it is desired to set the inlay. The cavity is then filled with wax 2, Fig. 1, the surface and margins of the wax filling being worked down and formed in exact similitude to the 70 desired form of the inlay. By means of a pin 3 embedded therein the wax positive impression of the tooth cavity is withdrawn and a metallic positive 3, preferably of silver Fig. 2, is cast using the wax impression as 75 a pattern so that the silver positive is an exact duplicate of the wax positive. The details of this process need not be given here since they are well known. It is seen that the silver positive which marks the completion 80 of the first stage of our process, in itself constitutes an accurate silver inlay for the tooth cavity and the explanation will now be directed toward the process of producing in porcelain an exact duplicate of the silver 85 positive.

In the process of casting the silver positive, a sprue 4 is formed thereon which is on the outside of the positive if it is set in the tooth cavity. For convenience, this surface 90 will be referred to hereafter as the outer surface, and the surface which corresponds to the shape of the cavity will be called the rear surface.

A short portion of the sprue 4 is preferably left on the outer surface of the silver positive as shown in Fig. 3 and the rear surface is given a comparatively heavy coating of wax 5 in which a pin 6 and wires 7 are embedded. Careful attention must be given 95 to the edges of the wax where it contacts with the silver, for accuracy at the margins of the final product depends on the accuracy of contact between wax and silver about these edges. The wax coating is left quite 100 thick at the edges adjoining the outer surface and these edges are trimmed off at an angle determined by the adjacent portions 105

of the outer surface of the positive so that the edges of the coating present a continuation of the outer surface of the positive of appreciable width. The pin 6 constitutes a 5 sprue to form the ingate to the mold in following steps of the process and the wires 7 are to form vents in the mold.

The silver positive with the wax coating and attached wires and pin is now invested 10 in a mold 8 of any suitable investment compound as shown in Fig. 4 and a cup 9 is hollowed out around the sprue to serve as a pouring gate. The sprue and vent wires are next withdrawn and the mold subjected to 15 heat for the purpose of driving out the wax coating 5, in the manner which is well understood by persons familiar with the art to which this invention pertains. At this stage of our process the mold 9 with the invested 20 silver positive 3 therein, is as shown in Fig. 5. The purpose of having a short portion of the sprue 4 on the outer surface of the silver positive is now clear, since with the removal of the wax, it serves to retain the 25 positive in proper position in the mold.

The mold as shown in Fig. 5 is now poured and for this casting we prefer to use gold or an alloy of gold and platinum for reasons which presently will be made clear. The 30 details of securing this casting need not be explained at length as the methods by which this may be done are well known. The melted gold or alloy is preferably drawn into the mold either by vacuumizing the 35 mold from below or by pressure or concussion above the mold, the essential thing being that the gold or alloy shall completely fill the space left by the evacuation of the wax so that the gold negative casting formed 40 over the rear surface of the silver positive will be an exact duplicate of the wax coating 5.

After cooling the mold is broken open and the silver positive is separated from the 45 gold negative clinging to its rear surface, preferably by the action of a solvent which will attack the silver but in which the gold is inert. For this we prefer to use nitric acid. The nitric acid dissolves the silver 50 from the gold negative leaving the latter, as shown in Fig. 6, a matrix block or negative 12 in which the cavity 13 is an exact duplicate of the cavity in the tooth from which the first wax impression was made. With 55 the securing of this matrix block the second stage of our process is completed. It will be understood that since the matrix block is a duplicate of the wax coating 5, it is only necessary to make the wax coating of the 60 required thickness to insure that the matrix block will be amply strong and resistant to deformation in ordinary handling and use. This is of the utmost importance for deformation of the matrix however slight is 65 destructive of accuracy in the inlay to that

extent. With the matrix block of our invention, deformation of the inlay is wholly avoided and the extreme care with which the foil matrices hitherto in use have had to be handled is unnecessary.

The third and last stage of our process 70 will now be described. The matrix block or negative is filled with the proper mixture of porcelain which is preferably tinted to simulate the color of the tooth in which the inlay is to be placed, and the whole subjected to heat in the usual manner. During the baking process the outer surface of the plastic porcelain is shaped to the required tooth curve, the edges 14 of the matrix block 75 serving as guide and giving the proper direction to the curve. Fig. 7 shows the matrix block with the completed porcelain inlay therein. After the formation of the porcelain inlay in the matrix block it is 80 necessary to separate it from the block and this is preferably done by subjecting the block and inclosed porcelain to a solvent which will attack the gold or alloy, but in no way injure the porcelain. For this we 85 prefer to use aqua regia and at the completion of this step of our process, the porcelain inlay as shown in Fig. 8 is secured. This is a duplicate, and on its rear 90 surface which forms the margins, a minutely exact duplicate of the wax impression of the tooth cavity first taken; and on being cemented into the cavity will be found to give perfect marginal contacts. In 95 the above explanation the metals used in performing our invention are stated to be silver and gold, but our invention is not to be limited to the use of those metals, as other materials may be used. In case a porcelain is used which requires a heat in 100 excess of the fusing point of gold, the negative or matrix block may be made of a gold or platinum alloy or other alloy possessed 105 of the requisite resistance.

We claim:

1. A form for baking and shaping a porcelain inlay for a given tooth cavity comprising a rigid cast matrix block having a recess therein the exact duplicate of the tooth cavity.

2. A form for baking and shaping a porcelain inlay for a given tooth cavity comprising a rigid cast matrix block formed of a material active in a reagent in which the inlay is inert and having a recess therein the exact duplicate of the tooth cavity.

3. The process of forming a porcelain inlay for a tooth cavity which consists in making a positive of said cavity, casting a rigid negative from said positive and forming said inlay in said negative.

4. The process of forming an inlay for a tooth cavity which consists in making a silver positive of said cavity, forming a rigid gold negative from said positive, bak-

ing a porcelain mixture in said negative to form said inlay and dissolving said negative away from said inlay.

5. The process of forming an inlay for a tooth cavity which consists in making a positive of said cavity, casting a negative upon said positive, removing the positive from the negative, treating a porcelain mixture in said negative to form said inlay and 10 removing said negative from said inlay.

6. The process of forming an inlay for a tooth cavity which consists in making a silver positive of said cavity, casting a gold negative upon said positive, separating the 15 positive from the negative by treating them with a solvent for the silver, heating a porcelain mixture in said negative to form said inlay and separating the negative from the inlay by treating them with a gold solvent.

20 7. The process of forming an inlay for a

tooth cavity which consists in making a wax positive of said cavity, casting a metallic positive therefrom, coating the rear surface of the metallic positive with wax, investing the coated positive in a mold, heating the 25 mold to remove the wax, filling the cavity thus formed with a different metal, removing the metallic positive from said second metal to form a metallic negative and treating a porcelain mixture in said negative to 30 form said inlay.

In testimony whereof, we have hereunto set our hands at Alameda, California, this 19th day of January, 1916.

ERNST R. SCHROEDER.
CHARLES M. MILLER.
